CONTROL VALVE MECHANISM FOR GAS FURNACES

Filed Sept. 22, 1930

INVENTOR.

GEORGE A. TUCK.
BY *Arthur L. S. Lee.*
HIS ATTORNEY.

UNITED STATES PATENT OFFICE

GEORGE A. TUCK, OF SAN FRANCISCO, CALIFORNIA

CONTROL VALVE MECHANISM FOR GAS FURNACES

Application filed September 22, 1930. Serial No. 483,605.

My invention relates to improvements in control valve mechanism for gas furnaces and the like, wherein a main control valve is provided with gas actuated operating means arranged to automatically open and close the main control valve, when a pilot burner valve is opened and closed respectively, whereby the supply of gas to a main burner may be automatically shut off when the pilot burner is extinguished.

10 The primary object of my invention is to provide an improved mechanism for operating a control valve to automatically open and close a gas supply connection simultaneously with the opening and closing of a pilot valve respectively.

Another object is to provide an improved valve control mechanism whereby a main control valve is actuated by the operation 20 of a thermostatically controlled pilot valve to open the control valve when the pilot is burning, and to automatically close the control valve when the pilot is extinguished.

A further object is to provide an improved 25 control valve operating mechanism actuated by a positive application of gas pressure in valve opening or closing direction.

Another object is to provide an improved mechanism of the character described wherein 30 in a single thermostatically controlled valve member is operative to control the supply of gas to a pilot burner, and to a control valve operating mechanism controlling the supply of gas to a main burner.

35 A further object is to provide an improved device of the character disclosed which is simple and economical in construction and which is simple, positive, and efficient in operation.

40 A still further object is to provide an improved structure embodying improved features of construction, arrangement, and operation.

I accomplish these and other objects by 45 means of the improved device disclosed in the drawings forming a part of the present application wherein like characters of reference are used to designate similar parts throughout the specification and drawings, 50 and in which—

Fig. 1 is a plan view of my improved control valve mechanism;

Fig. 2 is a broken longitudinal vertical section of the device as shown in Fig. 1; and

Fig. 3 is a vertical mid-section of the pilot valve structure, the figure being drawn upon a larger scale.

Referring to the drawings, the numeral 1 is used to designate in general a main supply pipe connected to a furnace burner 2 to supply gas thereto from a source of supply. The supply pipe 1 is provided with a suitable main valve 3 by which the supply of fuel to the burner 2 may be opened or closed manually or by mechanical means, as desired. The supply pipe 1 is also provided with a main control valve 4 mounted thereon upon the supply side of the valve 3 for opening and closing the supply of gas independently of the main valve 3.

The control valve 4 may be of any suitable construction wherein a movable member 6 is moved to seat upon a valve seat 5 to close the valve and to be unseated to permit a flow of gas through the valve. The member 6 is preferably provided with a stem 7 extending axially into a chamber 8 and connected to a movable partition 9 mounted within the chamber to divide the same into upper and lower compartments 11 and 12 respectively. The partition 9 is of any suitable structure adapted to yield under the pressure of gas supplied into one or the other of the compartments 11 or 12, whereby the partition may be displaced within the chamber to seat or unseat the valve member 6, and thereby close or open the valve 4.

A pilot burner 14 is mounted adjacent to the burner 2 upon a mounting member 16. Fuel is supplied to the pilot burner 14 through a pilot supply connection 17 provided with a pilot valve designated in general by the numeral 18. The pilot valve 18 is thermostatically controlled by suitable heat responsive mechanism, preferably such as illustrated in the drawings, and consisting briefly of a lever 19 pivoted near one end thereof and engaged at its short end by a rod 20 extending axially through the

burner 14, and at its opposite end by a movable valve member 21 mounted within the pilot valve 18. The construction and operation of the thermostatic valve operating means is fully described in a co-pending application filed September 22, 1930, Serial No. 483,606, and a further detailed description of said means is, therefore, omitted.

The thermostatically controlled pilot valve 18 is provided with pilot supply and delivery ports 22 and 23 to which supply and delivery portions of the supply connection 17 are connected respectively. The ports 22 and 23 are arranged to be covered by the movable valve member 21 to shut off the supply of gas to the pilot burner 14, and to be uncovered to permit a flow of gas through the valve 18 to said burner when the member 21 is moved to its open position.

The valve 18 is also provided with a pair of spaced control inlet ports 24 and 26 and with a pair of spaced control delivery ports 27 and 28. The inlet ports 24 and 26 communicate with a supply yoke 29 to which a supply connection 31 is connected to supply gas thereto, the connection 31 preferably being connected in any convenient manner to the pilot supply connection 17. The delivery ports 27 and 28 communicate with delivery connections 32 and 33 connected into the upper and lower compartments 11 and 12 of the chamber 8 respectively. The ports 27 and 28 are preferably arranged opposite and slightly offset with respect to the corresponding inlet ports 24 and 26. The valve member 21 is provided with reduced portions 34 and 36 providing passages by which gas may flow from the ports 24 and 26 to the ports 27 and 28 respectively when the valve member is moved to opening relation thereto, as hereinafter more fully described.

Vent passages 37 and 38 are formed in the valve 18 adjacent to the delivery ports 27 and 28 respectively. The vent 37 communicates with the port 27 through the passage formed by the reduced portion 34 of the valve member 21 when in one position, and the vent 38 communicates with the port 28 in a corresponding manner when the valve member 21 is moved to the opposite position, thereby opening the delivery connections 32 and 33 and the corresponding compartments of the chamber 8 to the atmosphere when the valve member is moved to corresponding positions.

The pilot connection 17 is provided with a pilot lighter 39 controlled by a valve 40, as in my co-pending application above referred to, and a suitable regulating valve 41 is mounted upon the supply connection 17 to regulate the flow of gas to the pilot valve 18.

In operation, the pilot burner 14 is started by opening the valves 41 and 40. Gas then

issuing from the lighter 39 is ignited and directed against the pilot burner 14. As the pilot burner is heated, the expansion of the burner member causes the rod 20 to be moved axially away from the adjacent end 70 of the lever 19, thereby permitting the lever to be displaced and the valve member 21 to be moved downwardly by means of a spring 43 from the closed position indicated in full lines in Fig. 2 to the open position as indicated in full lines in Fig. 3, thereby uncovering the ports 22 and 23 and permitting the flow of gas therethrough to the pilot burner. As soon as the ports 22 and 23 are uncovered, gas supplied therethrough to the 80 burner 14 is ignited and will normally maintain a continuous pilot flame so long as the valve member 21 remains in the open position.

While the valve member 21 is in closed 85 position, the reduced portion 34 is arranged to match with the supply port 24 and its corresponding delivery port 27, thereby permitting a flow of gas from the supply into the upper compartment 11 of the chamber 8. At the same time, the reduced portion 36 is moved to connect the delivery port 28 with its vent 38, while the corresponding inlet port 26 is covered by the body of the valve member 21 to close off the supply of 95 gas therethrough, as indicated in full lines in Fig. 2 and in dotted lines in Fig. 3 of the drawings. The pressure of the gas admitted through the delivery connection 32 to the compartment 11 causes the partition 100 9 to be displaced downwardly, thereby moving the valve member 6 to seat and close the control valve 4.

When the valve member 21 is moved to open position, as above described, the reduced portion 36 is moved downwardly to the position shown in full lines in Fig. 3 of the drawings, thereby causing the supply port 24 to be closed and to connect the delivery port 27 with its vent 37. At the same time, the reduced portion 34 is moved to communicate between the inlet 26 and the delivery port 28, the vent 38 being closed. In this position, gas flows through the ports 26 and 28 to the delivery connection 33 and thence to the compartment 12, thereby directing pressure upon the under side of the partition 9. As the vent 37 is then open and the pressure above the partition thereby released, the pressure applied upon the under side of the partition causes the partition to be displaced upwardly and the valve member 6 moved to disengage its seat 7 and open the valve 4.

So long as the pilot valve 21 remains in its open position, the gas pressure directed to the chamber 12 operates to maintain the control valve 4 in open position and the supply of fuel to the furnace burner 2 may 130

be regulated through the main valve 3 in the ordinary manner.

Should the pilot burner 14 become extinguished, the burner member will immediately cool and contract sufficiently to force the rod 20 against the lever 19 and thereby cause the lever to move the pilot valve member 21 to its closed position. As the member 21 is moved to closed position, the 10 pilot supply ports 22 and 23 are closed to prevent the escape of gas to the pilot burner, and at the same time the reduced portions 34 and 36 are moved to direct gas into the upper compartment 11 and to open the lower 15 compartment 12 to the atmosphere, thereby displacing the partition 12 downwardly and closing the control valve 4. In this manner, the supply of gas to the main burner 2 is cut off in back of the main regulating valve 3, and any manipulation of the 20 valve 3 will not permit an escape of gas through the burner 2 while the pilot is extinguished.

While I have illustrated only one embodiment of my improved mechanism, the specific details of construction and arrangement are of course subject to modification in numerous ways without departing from the spirit of my invention. I therefore do 25 not wish to be restricted to specific details of construction and arrangement as herein disclosed, but desire to avail myself of all modifications which may fall within the scope of the appended claims.

Having thus described my invention, what 30 I claim as new and desire to secure by Letters Patent is:

1. A control valve mechanism for gas furnaces comprising a supply pipe connected 35 to a gas burner and provided with a main control valve; valve actuating means mounted in connection with the control valve and actuated by gas pressure to open and close the valve; a pilot burner having a supply connection connected to the supply pipe; a pilot valve mounted in connection 40 with said pilot supply connection; means to automatically close the pilot valve when the pilot burner is extinguished; gas supply connections to deliver gas from the supply to opposite sides of the control valve actuating means to open and close the control valve; and valve means actuated by the pilot valve to open the connection to 45 the valve opening side of the control valve actuating means when the pilot valve is open, and to close said connection and open the connection to the valve closing side of 50 said actuating means when the pilot valve is closed.

2. A control valve mechanism for gas furnaces comprising a supply pipe connected 55 to a gas burner and provided with a main control valve; valve actuating means mounted in connection with the main control valve and yieldable under gas pressure directed 60 upon either side of said actuating means to open and close the control valve; a pilot burner having a supply connection connected to the supply pipe; a pilot valve mounted in connection with the pilot supply connection to open and close the same; means to automatically close the pilot valve when the 65

and yieldable under gas pressure directed upon either side of said actuating means to open and close the control valve; a pilot burner having a supply connection connected to the supply pipe; a pilot valve mounted 70 in connection with the pilot supply connection to open and close the same; means to automatically close the pilot valve when the pilot burner is extinguished; separate gas connections to deliver gas to opposite 75 sides of the control valve actuating means; valve means connected to and actuated by the pilot valve to open and close said gas connections, the connection to the valve opening side of the actuating means being automatically opened when the pilot valve is in 80 open position and the connection to the valve closing side being automatically opened when the pilot valve is moved to closed position.

3. A control valve mechanism for gas furnaces comprising a supply pipe connected to a gas burner and provided with a main control valve; valve actuating means mounted in connection with the main control valve and yieldable under gas pressure directed upon either side of said actuating means to open and close the control valve; a pilot burner having a supply connection connected to the supply pipe; a pilot valve mounted in connection with the pilot supply connection to open and close the same; means to automatically close the pilot valve when the pilot burner is extinguished; separate gas connections to deliver gas to opposite 90 sides of the control valve actuating means; valve means connected to and actuated by the pilot valve to open and close said gas connections, the connection to the valve opening side of the actuating means being automatically opened when the pilot valve is in open position and the connection to the valve closing side being automatically opened when the pilot valve is moved to closed position.

4. A control valve mechanism for gas furnaces comprising a supply pipe connected to a gas burner and provided with a main control valve; valve actuating means mounted in connection with the main control valve and yieldable under gas pressure directed upon either side of said actuating means to open and close the control valve; a pilot burner having a supply connection connected to the supply pipe; a pilot valve mounted in connection with the pilot supply connection to open and close the same; means to automatically close the pilot valve when the 120

pilot burner is extinguished; separate gas connections to deliver gas to opposite sides of the control valve actuating means; valve means connected to and actuated by the pilot 5 valve to open and close said gas connections, the connection to the valve opening side of the actuating means being automatically opened when the pilot valve is in open position and the connection to the valve closing 10 side being automatically opened when the pilot valve is moved to closed position; and separate vents adjacent to the gas supply connections to opposite sides of the control valve actuating means, and communicating 15 with the separate gas connections, each vent being closed when the valve means of said connection is moved to deliver gas to the corresponding supply connection and the other vent being opened to relieve the gas 20 pressure in the other supply connection.

5. A control valve mechanism for gas furnaces comprising a supply pipe connected to a gas burner and provided with a main control valve; valve actuating means 25 mounted in connection with the main control valve and yieldable under gas pressure directed upon opposite sides thereof to open and close the control valve; a gas supply connection having separate delivery connections 30 to opposite sides of the actuating means; a pilot burner having a supply connection connected to the supply pipe; and a pilot valve mounted in connection with the pilot supply connection to open and close the 35 same, said valve having a movable member movable to open and close the delivery connections to the control valve actuating means, the delivery connection to the valve opening side of said actuating means being 40 opened when the pilot supply connection is opened, and the delivery connection to the valve closing side of said actuating means being opened when the pilot supply connection is closed, whereby the control valve is 45 automatically opened and closed to correspond to the opening and closing of the pilot valve.

6. A control valve mechanism for gas furnaces comprising a supply pipe connected to 50 a gas burner and provided with a main control valve; valve actuating means mounted in connection with the main control valve and yieldable under gas pressure directed upon opposite sides thereof to open and close the control valve; a gas supply connection having separate delivery connections to opposite sides of the actuating means; a pilot burner having a supply connection connected to the supply pipe; a pilot valve 55 mounted in connection with the pilot supply connection to open and close the same, said valve having a movable member movable to open and close the delivery connections to the control valve actuating means, the delivery connection to the valve opening side 60

65

of said actuating means being opened when the pilot supply connection is opened, and the delivery connection to the valve closing side of said actuating means being opened when the pilot supply connection is closed, whereby the control valve is automatically opened and closed to correspond to the opening and closing of the pilot valve; and means to automatically close the pilot valve when the pilot burner is extinguished.

7. A control valve mechanism for gas furnaces comprising a supply pipe connected to a gas burner and provided with a main control valve; valve actuating means mounted in connection with the main control valve and yieldable under gas pressure directed upon opposite sides thereof to open and close the control valve; a gas supply connection having separate delivery connections to opposite sides of the actuating means; a pilot burner having a supply connection connected to the supply pipe; a pilot valve mounted in connection with the pilot supply connection to open and close the same, said valve having a movable member movable to open and close the delivery connections to the control valve actuating means, the delivery connection to the valve opening side of said actuating means being opened when the pilot supply connection is opened, and the delivery connection to the valve closing side of said actuating means being opened when the pilot supply connection is closed, whereby the control valve is automatically opened and closed to correspond to the opening and closing of the pilot valve; and thermostatically controlled means to automatically close the pilot valve when the pilot burner is extinguished.

In witness whereof, I hereunto set my signature.

GEORGE A. TUCK.
